Primary Examiner — Elizabeth J Oswecki

(57) **CLAIM**

The ornamental design for a high heel, as shown and described.

DESCRIPTION

FIG. 1 is a perspective view of a high heel showing my new design;

FIG. 2 is a left side view thereof;

FIG. 3 is a right side view thereof;

FIG. 4 is a front view thereof;

FIG. 5 is a right side view thereof;

FIG. 6 is a top view thereof; and,

FIG. 7 is a bottom view thereof.

The broken lines shown in the drawings depict portions of the high heel in which the design is embodied that form no part of the claimed design.
